FIG. 1 is a back underside perspective view of a connector barrel showing our new design;

FIG. 2 is a front overhead perspective view of the connector barrel of FIG. 1;

FIG. 3 is a top plan view of the connector barrel of FIG. 1; FIG. 4 is a bottom plan view of the connector barrel of FIG. 1;

FIG. 5 is a right side elevational view of the connector barrel of FIG. 1;

FIG. 6 is a left side elevational view of the connector barrel of FIG. 1;

FIG. 7 is a front elevational view of the connector barrel of FIG. 1; and, FIG. 8 is a back elevational view of the connector barrel of FIG. 1.

The broken lines shown in the drawings show portions of the battery module connector barrel which form no part of the claimed design.

The shade lines in the Figures show contour and not surface ornamentation.

Where the dot-dash broken lines abut the shaded surface it is understood that those broken lines represent an unclaimed boundary between claimed and unclaimed surfaces.
